UNITED STATES PATENT OFFICE.

MAX BREMER, OF ELGIN, ILLINOIS, ASSIGNOR TO THE WESTERN CASKET HARDWARE COMPANY, OF ELGIN, ILLINOIS, A CORPORATION OF ILLINOIS.

REINFORCED CASKET-HANDLE.

No. 846,545.

Specification of Letters Patent.

Patented March 12, 1907.

Application filed April 13, 1906. Serial No. 311,435.

To all whom it may concern:

Be it known that I, MAX BREMER, a citizen of the United States, residing at Elgin, in the county of Kane and State of Illinois, have 5 invented a certain new and useful Improvement in Reinforced Casket-Handles, of which the following is a specification.

My invention relates to handle devices for caskets and the like, and has for its object to 10 provide new and improved constructions in devices of that character.

The invention has more particularly for its object to provide strengthening or reinforcing means for the parts of the handle to 15 prevent accidental breaking. Ordinarily in devices of this character the visible parts are constructed of some soft metal which may be cast or worked into ornamental forms; but unless properly reinforced these parts are 20 likely to break away or tear at the joints where the strain comes.

My invention contemplates providing an efficient reinforcing means.

The invention is illustrated in the accompanying drawings, wherein—

Figure 1 is an elevation of the device with parts broken away for purposes of illustration; Fig. 2, a section on line 2 2 of Fig 1; Fig. 3, a rear view of one of the sockets; Fig. 30 4, a side elevation of the socket-brace; Fig. 5, a side elevation of a hanger-brace, and Fig. 6 a section on line 6 6 of Fig. 2.

Like parts are indicated by the same letter in all the drawings.

35 The device is shown as comprising a handle A, sockets B B, and hangers C C. It will be understood that there may be any number of sockets and hangers associated with a single handle. The sockets and their associated parts are the same; so it will not be necessary to describe but one of these combinations of parts.

The socket will ordinarily be made of some soft metal which can be given an ornamental 45 design. It is here shown as a dish-shaped or recessed plate having the central aperture B', the material on each side forming bearings B² B² for the pivot B of the hanger. The socket has preferably the screw-holes B³ B³.

50 The body of the hanger will also preferably be of some soft metal and has a perforation for the pivot D. The upper end of the hanger is preferably rounded at C', so as to turn easily in the aperture B' of the socket.

It may also be provided with the shoulder C² 55 to limit its movement upward. The other end of the hanger is in the form of a ring C³, which surrounds the handle A, being secured thereto by the screw C⁴.

Embedded in the hanger is a reinforcing-brace E, having a ring E' at one end corresponding to the ring C³, the other end following the curvature of the part C' and lying between the outside of the hanger and a projection C⁵, formed on the inside of the hanger 65 above the pivot-hole for the pivot B. The inner end of the reinforcing-brace E is provided with the hook E², adapted to engage with the reinforcement associated with the socket. This reinforcement consists, preferably, of the plate or horizontal strip F, having screw-holes F' F' corresponding to the holes B' B³ of the socket and integral therewith an upstanding part or projection F², having the aperture F³ and the two perforated 70 lugs F⁴, which lie within and reinforce the bearings B² B² of the socket. The pivot 75 D, it will be understood, extends through the perforations in these reinforcing-lugs.

When the handle is lifted, it will be obvious 80 that a strain will be exerted at the connections between the hanger and the socket, the hanger and the handle, and the socket and the object to which it is attached. My reinforcing devices take up all of this strain and 85 effectually prevent the tearing out or the breaking away of the softer metal parts. The connection between the hanger and the handle A is reinforced by the ring E', that between the parts at the pivot D by the lugs F⁴, 90 and the crushing and tearing strains due to the impingement of the hanger against the socket is taken up by the end of the reinforcing-brace E, the hook E², and the part F² of the socket-brace, the vertical strain being 95 taken by the end of the brace E above the hook, while the handle is prevented from being crushed and pulled out sidewise by the hook E², which extends around the part F². The connection of the socket to the casket 100 will be made through the apertures B³ in the socket, this connection being reinforced by the part F of the bracing structure. It is understood, of course, that these bracing structures are of some tenacious material, such as 105 steel.

I wish it to be understood that I do not desire to be limited to the exact details of

construction shown and described, for obvious modifications will occur to any person skilled in the art.

I claim—

- 5 In a handle device, the combination of a socket with a hanger, a pivot for the hanger, a reinforcing-plate in the socket, perforated lugs on said plate forming bearings for the pivot, a slot in said plate, a reinforcement in

the hanger provided with a curved part lying to over and partly around the pivot, and a lug on the end of said reinforcement adapted to extend into the slot in the socket-reinforcing plate when the handle is lifted.

MAX BREMER.
